VEGETABLE PARING MACHINE

John Hardt, Lachine, Quebec, Canada

Application March 29, 1949, Serial No. 84,165
In Canada April 1, 1948

2 Claims. (Cl. 146—50)

1

Introduction

This invention relates to improvements in paring machines.

While there are, at the present time, many forms of paring machines adapted to pare vegetables or the like using drums with abrasive inner linings, most of these still present a considerable problem for their efficient cleaning. Moreover, when the abrasive lining or coating requires renewal, either through wear or damage, the machines have to be partially dismantled and in some cases returned to the factory for repair.

Objects

It is the principal object of the present invention to provide a paring apparatus that includes an abrasive inner lining that may be easily removed for cleaning or repair. A further object of the invention is to provide a lining that may be removed and replaced in sections so that wear or damage of some particular portion of the abrasive lining may be repaired without the necessity of replacing the entire unit.

Applicant's development

The invention is embodied in a paring apparatus having a drum adapted to contain vegetables or the like for paring and including means for agitating said vegetables within the drum. In accordance with the invention there is a removable abrasive inner lining that fits within the inner periphery of the drum. In a preferred form of the invention the removable lining comprises a plurality of arcuate sections having abrasive surfaces.

These arcuate sections are arranged so as to contact vegetables placed within the drum and are retained in position by a pair of retaining rings, one disposed at the bottom of the sections and one at the top. The edges of the arcuate sections that are adapted to meet the top and bottom retaining rings, and the adjacent faces of the retaining rings are bevelled to have opposing angles. The angle on the arcuate sections is directed away from the inner face of the drum and the angle on the retaining rings is directed towards the inner face of the drum. These angles are so arranged, so that the top and bottom rings retain the arcuate sections in position and force them towards the inner surface of the drum. A cover portion having a flange adapted to fit within the drum and rest upon the top ring is secured in place by screws or the like when the machine is in operation, thus holding in place the lining assembly including the sections and rings.

The arcuate sections may be made from any suitable material that may be impregnated with an abrasive agent, for example plastic, composition stone, or the like. It is also contemplated

2

that the sections may be made of metal formed to constitute an abrasive surface, or having an abrasive material adhesively secured thereto.

Detailed description

Having thus generally described the nature of the invention particular reference will be made to the accompanying drawings, and in which:

10 Figure 1 is a perspective view illustrating a preferred form of a paring apparatus embodying the invention.

Figure 2 is a sectional view of a paring drum as in Figure 1, having an inner lining constructed according to the invention.

15 Figure 3 is an enlarged sectional view of Figure 1 on the line 3—3.

Figure 4 is an exploded view of a vegetable paring drum including a sectional inner lining constructed according to the invention and illustrating the relationship of the component parts.

20 Figure 5 is an enlarged section of Figure 1 on the lines 5—5 to further illustrate the construction thereof.

25 Referring particularly to the drawings, 10 designates a drum adapted to contain vegetables for paring. A stand 12 supports the drum 10 at a convenient height and also supports a motor 14 which is adapted through a system of belting 16 and gearing 18 to rotate a vegetable agitating plate 20. The plate 20 includes a plurality of corrugations or raised members 22 which are adapted to engage and impell the vegetables against the inner surface of the drum. The rotary plate 20 is removably mounted within the drum 10 by means of a slot 23 in the lower portion of the plate 20 and a key 26 secured to the shaft 28. The shaft extends from the gears 18 through a stuffing box 29 into the interior of the drum 10. The bottom of the drum 10 is formed 30 with an upstanding annular flange 30. The flange 30 in combination with the stuffing box 29 prevents water or waste from leaking into the rotating mechanism. The removable inner lining in the drum 10 comprises a plurality of arcuate

35 sections 40 and 41. The sections 40 and 41 are composed of abrasive impregnated material and in the preferred construction illustrated in Figure 3 comprise five plain sections 40 and one opening containing section 41. It will of course be understood that any amount of sections may be used, from one to ten or more, the number depending on the size of the drum and the relative size of the sections that may be easily handled. The sections 40 and 41 are retained 40 within the drum 10 by a top retaining ring 42 and a bottom retaining ring 44. The top and bottom edges of the sections 40 and 41 are formed at an angle sloping away from the inner face of the drum. The face of the top retaining ring 42

45 adapted to engage the top edge of the sections 55 within the drum 10 by a top retaining ring 42 and a bottom retaining ring 44. The top and bottom edges of the sections 40 and 41 are formed at an angle sloping away from the inner face of the drum. The face of the top retaining ring 42 adapted to engage the top edge of the sections

40 and 41 and the face of the bottom retaining ring 44 adapted to engage the bottom edge of the sections 40 and 41 are formed at an angle sloping towards the inner face of the drum. In the preferred form of the device the angle on the sections 40 and 41 and the top 42 and bottom retaining ring 44 is approximately 45°. The arrangement of the opposing angles on the top 42 and the bottom 44 retaining ring and the arcuate sections 40 and 41 thus tends to retain the arcuate sections 40 and 41 securely in place and force them against the inner face of the drum 10.

The arcuate section 41 positioned within the drum relative to the opening 11 in the drum 10 includes an opening 50 in register with the opening 11 through which vegetables are adapted to be removed from the drum. A door 54 hingedly attached as at 46 to the drum 10 is adapted to cover the opening 11. A section of abrasive impregnated material 52 secured to the inner face of the door 54 is adapted to fit within the opening 50 when the door 54 is closed and thus complete the abrasive surface of the section 41 within the drum 10. A latch 58 is adapted to secure the door 54 in the locked position when the machine is in operation. A drum cover 46 having a centrally disposed flanged opening for the insertion of vegetables, includes a flange portion 48 which fits within the inner periphery of the drum 10 and rests upon the top retaining ring 42.

Preferably the drum cover 46 is secured to the drum 10 by screws 43 engaging tapped holes in the flange 48, and the top retaining ring 42, the arcuate sections 40 and 41, and the bottom retaining ring 44 are thus locked in position.

Operation

Referring particularly to Figure 4, when it is necessary to remove any or all of the arcuate sections 40 or 41, the door 54 is opened. The screws 43 are removed from the cover 46 and the cover 46 is removed. The top retaining ring 42 is then removed allowing for the removal of the sections 40 and 41 as required.

With the additional removal of the bottom retaining ring 44 and the rotary table 20 the interior of the drum is completely clear for complete and satisfactory cleaning.

The easy complete removal of the entire abrasive lining and the rotary table thus makes the cleaning and servicing of the drum assembly a simple matter. The dividing of the inner lining into several portions allows for the replacement or repair of any of the portions individually instead of dismantling and repairing the entire unit as was necessary in prior apparatus of this nature.

I claim:

1. A potato peeling device having a potato receiving drum including a substantially vertical cylindrical side wall, a floor integrally connected at its lower end to the side wall permanently closing the bottom of the drum and forming a corner with the side wall, the side wall terminating at its upper end in a substantially horizontal annular rim defining an open mouth, and a removable cover adapted at least partially to close said mouth, and means for agitating the potatoes in the drum including an impeller close to said floor removably connected to a drive shaft, the floor including a bearing opening receiving said shaft, said shaft extending downwardly through said opening, and means below the floor for driving the shaft, a bottom circu-

lar continuous and unbroken essentially rigid connection-free retaining ring fitting snugly but freely in the drum in the corner between the floor and side wall, said ring having a bottom bearing face resting on said floor and an outer peripheral bearing face resting in contact with the side wall, said ring having an upper bevelled face extending downwardly and outwardly, to form between it and the side wall an annular wedge-shaped groove, a plurality of separate arcuate segments each having a vertical edge juxtaposed to but unkeyed to that of an adjacent segment making up a cylindrical lining for said side wall and fitting close to each other and each having its inner surface in direct contact with the side wall, each of said segments having a lower bevelled edge giving the segment a tapered lower end engaging in said groove and being held against the wall by the bevelled edge of said lower ring, each of said segments also having a bevelled upper edge giving the segment a tapered upper end, an upper circular continuous and essentially rigid unbroken connection-free retaining ring of a size to fit snugly within said drum and having an outer peripheral bearing face in contact with said side wall, said upper ring being unconnected to the drum and having an upwardly and outwardly extending bevelled lower face adapted to bear against the bevelled upper edge of the segments and to form with the side wall a receiving groove for the tapered upper ends of the segments, said upper ring having an upper face engaged by said cover, the dimensions of the rings and segments in relationship to the side wall being such that the upper ring is spaced from the rim of the side wall thus leaving an upper portion of the side wall uncovered by the lining or rings, said cover having an annular skirt extending downwardly within said drum, said skirt having a bearing face fitting against the side wall, the skirt having a lower peripheral rim adapted to bear on the upper face of said upper ring whereby the weight of the cover resists any upward movement of the ring, the segments thus being held in place solely by the wedging action of the upper and lower rings with the weight of the cover bearing on the upper ring to retain it from upward movement, and the inner side of the drum wall being cylindrical and unobstructed whereby the upper ring and the segments are freely removable upwardly through the drum mouth upon removal of the cover.

2. A potato peeling device according to claim 1, in which the cover is provided with an annular outstanding horizontal flange adapted to overlie the top edge of the side wall.

JOHN HARDT.
